UNITED STATES PATENT OFFICE

2,608,164

OVERHEAD CARRIER

Forrest E. Johnston, South Gate, Calif.

Application January 5, 1951, Serial No. 204,629

3 Claims. (Cl. 105—242)

1

The present invention relates to new and useful improvements in overhead carriers designed particularly for use in meat packing plants to facilitate the handling, weighing and moving the meat products from one department of the packing plant to another, or for the delivery of articles to a loading platform.

An important object of the invention is to provide an overhead carrier including a frame provided with a wheel at its upper end for travelling on an overhead track and supporting a basket at the lower end of the frame provided with locking means for holding the basket in a horizontal position and which may release the basket for swinging into a vertical position whereby the baskets may be nested for storing in a compact form, when not in use.

A further object is to provide a device of this character of simple and practical construction which is efficient and reliable in use, strong and durable, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view;

Figure 2 is a side elevational view;

Figure 3 is an enlarged transverse sectional view taken on the line 3—3 of Figure 1;

Figure 4 is a top plan view showing the basket swung into a vertical position;

Figure 5 is a vertical sectional view taken on the line 5—5 of Figure 4; and,

Figure 6 is a transverse sectional view taken on the line 6—6 of Figure 5.

Referring now to the drawings in detail, wherein for the purpose of illustration, I have disclosed a preferred embodiment of the invention, the numeral 5 designates a substantially U-shaped inverted frame including a pair of legs 6 having converging upper ends 7 united with each other by a plate 8.

A hanger bracket 9 of strap metal is formed with a horizontal flange 10 at its lower end positioned on top of plate 8 and swively connected thereto for horizontal swinging movement of the frame 5 by means of a headed pin 11 having a nut 12 threaded at its lower end.

The upper end of bracket 9 is formed with an inverted U-shaped yoke 13 in the sides of which a shaft 14 is supported and on which a wheel 15

2

is rotatably mounted for travelling on an overhead track or rail 16.

The lower ends of legs 6 are formed with eyes 17 for receiving pins 18 having threaded inner ends 19 threaded into brackets 20 which are welded or otherwise suitably secured to the sides of a sheet metal basket 21 at the upper side edges thereof and substantially mid-way between the ends of the basket. The outer ends of pins 18 are

10 formed with head 22 to hold the eyes 17 thereon.

The upper edges of basket 21 are formed with an outwardly rolled flange 23 and on top of which a U-shaped catch 24 is swingably mounted for inward and outward swinging movement adjacent 15 each leg 6 of frame 5 by means of a bearing 25 welded or otherwise secured on top of the flange 23 and whereby the basket is locked to the frame 5 to hold the basket in a horizontal suspended position at the lower ends of the frame.

20 One end of basket 21 is open and formed at its open end with an outwardly projecting flange 26 at each side of the basket and with the outer edges of the flanges sloping toward notches 27 to form cams on which the legs 6 ride to enter 25 the notches when the basket is swung into a vertical position, as shown in Figure 5 of the drawings.

In the operation of the device the basket 21 is locked in its horizontal position by swinging 30 the U-shaped catches 24 outwardly to straddle the lower ends of legs 6 of frame 5 and articles may then be loaded into the basket and transported from place to place on the overhead rail or track 16.

35 When it is desired to store the baskets, the catches 24 are swung inwardly to release the legs 6 of the frame and the basket is then swung into a vertical position with its open end uppermost. The legs ride on the cams at the edges of the flanges and are sufficiently resilient to flex and enter the notches 27 of flanges 26 to thus lock the basket in its vertical position and the baskets may then be nested and stored in compact form in the manner indicated in Figure 5.

40 In view of the foregoing description taken in conjunction with the accompanying drawings it is believed that a clear understanding of the device will be quite apparent to those skilled in this art. A more detailed description is accordingly deemed unnecessary.

45 It is to be understood, however, that even though there is herein shown and described a preferred embodiment of the invention the same 50 is susceptible to certain changes fully comprehended within the spirit and scope of the invention.

hended by the spirit of the invention as herein described and the scope of the appended claims.

Having described the invention, what is claimed as new is:

1. An overhead carrier comprising an inverted U-shaped frame having a wheel at its upper end adapted for travelling on an overhead track, a rectangular shaped basket pivotally connected adjacent its upper side portions to the lower ends of the frame for swinging the basket vertically into either a horizontal or a vertical position, and catch means carried by the basket respectively adjacent its pivoted portion and at an end portion and engaging the frame to selectively hold the basket in either a horizontal or a vertical position.

2. An overhead carrier comprising an inverted U-shaped frame having a wheel at its upper end adapted for travelling on an overhead track, a rectangular shaped basket pivotally connected adjacent its upper side portions to the lower ends of the frame for swinging the basket vertically into either a horizontal or a vertical position, and a catch on the basket adapted for engaging

5 the frame for holding the basket in a horizontal position.

10 3. An overhead carrier comprising an inverted U-shaped frame including a pair of leg portions and having a wheel at the upper portion of the frame adapted for travelling on an overhead track, a rectangular shaped basket pivotally connected adjacent its upper side portions to the lower ends of the legs for swinging the basket vertically into either a horizontal or a vertical position, and a U-shaped catch pivotally carried by the basket adjacent its pivoted portion and adapted to straddle an adjacent leg to hold the basket in a horizontal position.
